BLOWER FOR CLOTHES PRESSING MACHINES

Foster Laughlin, Dayton, Ohio

Application August 30, 1941, Serial No. 409,049

1 Claim. (CL 230—116)

My invention relates to new and useful improvements in blowers for clothes pressing machines.

An important object of my invention is the provision of a clothes pressing machine that includes means for passing atmospheric air through the garment to rapidly dry the same after it has been pressed in the conventional manner by forcing steam under pressure therethrough. Another object of the invention is to provide an improved blower construction which is compact, durable and efficient in operation.

Other objects and advantages of my invention will be apparent during the course of the following description.

In the drawings, forming a part of this specification, and wherein like numerals are employed to designate like parts throughout the same:

Figure 1 is a front elevation of a device embodying my invention,

Figure 2 is an end elevation of a pressing machine embodying the blower of my invention,

Figure 3 is a longitudinal sectional view of the air blower embodying my invention, and

Figure 4 is a transverse vertical sectional view taken on line 4—4 of Figure 3.

In the accompanying drawings, wherein for the purpose of illustration is shown a preferred embodiment of my invention, the numeral 10 designates the supporting base of a clothes pressing machine. The supporting base is of substantially standard construction comprising a box-like support 11 having a top 12 of substantially larger dimension, which top supports the lower stationary pressing buck 13. Rockably supported above the buck 13 is an upper buck 14 which is movable toward and away from the lower buck in the conventional manner. The longitudinally spaced upstanding arms one of which is shown at 16 formed on the support 11 rearwardly of the top 12 are connected at their free end thereof by a rod 17 which pivotally supports the rocker arm 18. The upper end of the rocker arm is bifurcated to provide the arcuately curved fingers 21 which are bolted or otherwise fixedly secured to the upper buck 14. The portion 22 of the arm extends downwardly and rearwardly and terminates in an integral counterweight 23 of sufficient weight to normally hold the upper buck in the raised or elevated position illustrated in the drawings.

Steam is supplied to the lower buck through a pipe 70 which connects with the upstanding portion 67 of the pipe 64 and extends forwardly

along the side of the base 11 to connect with a valve 71 constructed and operated in the manner hereinbelow described. The valve is mounted at the side of the machine to the right of the operator and a foot lever 72 is pivoted to the machine and operatively associated with the valve through the medium of a linkage 73. When the operator depresses the pedal 72 the linkage 73 will open the valve 71 to permit the steam from the pipe 70 to flow into the pipe 74 which extends along the mentioned side of the base and terminates rearwardly thereof. An elbow connection 75 is connected to the end of the pipe 74 and the pipe 76 also connecting with the elbow extends horizontally along the rear wall of the base and in substantially spaced parallel relation with the portion 65 of the pipe 64. The pipe 76 terminates at the opposite side of the base and the elbow connection 77 applied thereto also connects with an upstanding length of pipe 78 which terminates at substantially the level of the top 12 of the supporting base to receive the elbow connection 79. The pipe 80 also connected to the elbow 79 extends inwardly along the left side of the base which pipe terminates directly below the lower buck. From thence the steam line leads to the interior of the lower buck in a known manner.

It may thus be seen that steam may be supplied to the lower buck independently of the movement of the upper buck by the mere expediency of depressing the foot pedal 72. As soon as the valve 72 is opened to permit communication between the pipes 79 and 74 the steam will flow directly into the lower buck and be discharged through the top surface thereof and against a garment placed thereon.

I have found that the garment dries more rapidly and smoother if atmospheric air is caused to pass therethrough under pressure after the steam has been applied thereto. I have therefore mounted a blower 84 on a standard 85 located rearwardly of and to the left of the presser. The blower is unique in its construction and this construction is best illustrated in Figures 3 and 4. In view of the fact that it is at all times necessary to maintain an adequate supply of steam for the pressing operations I propose to use a blower which is steam operated and which is connected in the steam conducting system hereinabove described. By operating the blower by means of steam in the system a substantial saving is permitted and a highly efficient operation is achieved.

As best illustrated in Figure 3, the blower cas-

ing 86 is divided into an air chamber 87 and a steam chamber 88, the chambers being separated by a vertical partition wall 89. A spindle 90 is centrally journaled for rotation in the partition 89 and the opposite ends thereof extend into the air and steam chambers thereof. A steam operated turbine rotor 91 is fixedly mounted on the end of the spindle extending into the steam chamber. Steam is supplied to the chamber 88 through the pipes 92 and 93. The pipe 92 connects with the pipe 64 hereinabove referred to and the pipe 93 connects with the casing 86. The pipes 92 and 93 are connected by a valve of the foot operated type, which, when open, permits the steam to flow through the pipe 92 and through the valve and through the pipe 93 to the steam chamber 88 where it impinges against the blades of the turbine rotor 91 to drive the same. An exhaust conduit 96 connects with an outlet opening in the upper portion of the steam chamber 88 for the escape of steam while a pipe 97 connects with a bottom opening therein for draining condensate from this chamber. Due to the connection of the turbine rotor 91 with the fan 98 through the spindle steam operation of the rotor will effect blower rotation of the fan. At its center, the outer wall of the fan chamber is provided with an intake opening 99 whereby air is drawn into the air chamber for discharge through the conduit 100 into the lower buck.

It is customary in the art to provide an auxiliary device for steaming the shoulders of a garment, which device is commonly known as a puffiron. I have illustrated such a device in connection with my pressing machine, which device is here designated by the numeral 102. This device is conventional in the art and a detailed description of the same is therefore thought to be unnecessary. I carry steam to the puffiron through the pipes 103 and 104, the pipe 103 being connected to the steam supply pipe 60 and the pipes 103 and 104 being connected by an elbow 105. The terminal end of the pipe 104 is connected to a valve 106 of the type illustrated in Figure 7 and the valve is provided with an upward extension 107 to flow from the valve and into the puffiron. The valve 106 is operated by the foot pedal 108 in the manner described above, the pedal being connected to the stem 48 of the valve by means of the connecting rod 109.

The operation of the device is as follows:

The operator first places the garment to be pressed on the top surface of the lower buck 13 and then places his foot on the middle pedal 26 to lower the top buck 14 into pressed relation with the top of the garment. The usual pro-

cedure when operating the foot lever 24 is to manually grasp the handle 39 and to pull downwardly thereon to aid in lowering the upper buck. As soon as the upper buck is moved to the lowered position, the operator removes his foot from the pedal 26 and manually holds the upper buck in the lowered position while the steam enters the upper buck through the automatically opened valve 49. When the operator removes his foot from the pedal 26 he places it on the lever 72 to open the valve 71 whereby the steam may enter the lower buck.

After the garment has been pressed in this manner, the operator removes his foot from the lever 72 and permits the upper buck to move to the raised position whereby to automatically close the valve 49. The operator then places his foot on the lever 95 to cause the steam to bypass into the steam chamber of the blower whereby to drive atmospheric air under pressure into the lower buck to dry the garment thereon.

It is to be understood that the form of my invention herewith shown and described is to be taken as a preferred example of the same and that various changes in the size, shape and arrangement of parts may be resorted to without departing from the spirit of my invention nor the scope of the appended claim.

Having thus described my invention, I claim:

30 A blower of the character described comprising a cylindrical housing, a standard formed integral with the housing and adapted to support the latter with its axis disposed horizontally, the said housing having one end completely closed and the opposite end closed with the exception of a restricted central opening, a transverse partition formed intermediate the ends of the housing and in registration with the partition dividing the interior into a steam chamber and an air chamber, an axially extending spindle rotatably journaled in the center of the partition having an end portion projecting into the steam chamber and an opposite end portion extending into the air chamber, the bottom of the steam chamber having an inlet, a steam supply pipe connected with the said inlet, the top of the said steam chamber having an exhaust outlet, a steam rotor wheel fixed on the spindle within the steam chamber for rotation by the steam admitted through the inlet, the said air chamber having an outlet nozzle at the lower portion thereof, and a fan fixed to the spindle within the air chamber adapted to draw air through the central end opening therein and discharge the same under pressure through the bottom outlet of the air chamber.
